[57] CLAIM

The ornamental design for a multiple compartment trash container, as shown and described.

DESCRIPTION

FIG. 1 is an exploded top perspective view of a multiple compartment trash container showing our new design; FIG. 2 is a front elevational view thereof, the rear being identical to the front with the exception of the lower drawer;

FIG. 3 is a left side elevational view thereof;

FIG. 4 is a right side elevational view thereof; and,

FIG. 5 is a top plan view thereof.

The undisclosed bottom is flat and unornamented.

FIG. 1.

FIG. 3.

FIG. 2.

FIG. 5.

FIG. 4.
